CLAIM

(52) **U.S. Cl.**

The ornamental design for a garment box insert, as shown and described.

(53) **USPC** **D9/456**

DESCRIPTION

(58) **Field of Classification Search**

FIG. 1 is a perspective view of a garment box insert according to the present design.

USPC D9/430, 431, 432, 433, 434, 456, 499;

FIG. 2 is a front view of the garment box insert shown in FIG. 1;

220/579; 223/71

FIG. 3 is a rear view of the garment box insert shown in FIG. 1;

CPC B65D 25/00; B65D 85/18

FIG. 4 is a top view of the garment box insert shown in FIG. 1;

See application file for complete search history.

FIG. 5 is a bottom view of the garment box insert shown in FIG. 1;

(56) **References Cited**

FIG. 6 is a side view of the garment box insert shown in FIG. 1, the opposite side view being a mirror image thereof; and,

U.S. PATENT DOCUMENTS

FIG. 7 is the opposite side view referenced above with regard to FIG. 6.

In the drawings, the broken lines depict environmental subject matter only and form no part of the claimed design.
